UNITED STATES PATENT OFFICE.

WILLIAM WHIGHAM, OF PITTSBURGH, PENNSYLVANIA, ASSIGNOR TO THE SHENANGO MANUFACTURING COMPANY, OF PITTSBURGH, PENNSYLVANIA, A CORPORATION OF PENNSYLVANIA.

STORAGE TANK OR CONTAINER.

1,118,714.

Specification of Letters Patent.

Patented Nov. 24, 1914.

Application filed July 12, 1911. Serial No. 638,225.

To all whom it may concern:

Be it known that I, WILLIAM WHIGHAM, of Pittsburgh, Allegheny county, Pennsylvania, have invented a new and useful Storage Tank or Container, of which the following is a full, clear, and exact description, reference being had to the accompanying drawings, forming part of this specification, in which—

10 Figure 1 is a longitudinal section showing a storage tank or container embodying one form of my invention; Fig. 2 is a section on the line II—II of Fig. 1, and partly broken away; Fig. 3 is a view similar to Fig. 1 but showing only a portion of the body of the container and also illustrating a modified construction; Fig. 4 is a section on the line IV—IV of Fig. 2; and Fig. 5 is a longitudinal section showing still another modification.

20 My invention has relation to storage tanks or containers, and more particularly to tanks or containers for storing acetylene gas which is absorbed by acetone or other suitable absorbent.

25 The object of my invention is to provide a tank or container of this character which will be strong and free from seams, in which the valve seat is formed within the solid metal head of the container; in which the parts are effectively protected against injury in shipment and in use; and in which means are provided for the collection of the gas at or near the extreme upper portion of the tank and entirely above the level of the solvent.

30 The nature of my invention will be best understood by reference to the accompanying drawings, which will now be described, 40 it being premised, however, that various changes can be made in the details of construction and arrangement of the parts without departing from the spirit and scope of my invention as defined in the appended claims.

45 In these drawings, the numeral 2 designates the body of the container, which is preferably formed from a seamless tube having the end portions thereof forced inwardly and worked to form the integral heads 3 and 4. The head 4 is formed with the solid metal reduced neck portion 5, which is preferably exteriorly threaded to receive a screw cap 6. This neck portion 5 is drilled or bored through to form the central opening

7 having a screw thread to receive the threaded shank 8 of the usual pressure gage 9, which gage is contained within the outer portion of the cap 6, and may be read through the opening 10 in the end of the cap.

50 In constructing the tank or container, after the opening 7 has been bored or drilled, an opening or passage 11 is drilled obliquely through the neck 5 and head 4, the outer end of said opening intersecting the opening 7. This opening 11 is adapted to receive a gas collector pipe or tube 12, whose inner end can be extended into the body of the tank closely adjacent to its upper wall, 70 the outer end of said tube lying within an enlarged portion or cavity 13, where the opening 11 joins the opening 7. The outer end portion of the pipe or tube 12 is preferably screw-threaded, or is provided with 75 other suitable means for engagement with a suitable socket or key, by means of which the pipe or tube can be withdrawn at any time in case stoppage or other causes renders this necessary.

80 14 designates a valve stem, having at its inner end the valve 15. To receive the valve stem and valve the solid metal of the neck 5 is bored or drilled from one side to form an opening which will communicate at its inner end with the cavity 13. A bushing 16 is preferably provided to act as a valve seat, although this seat may be formed in the metal of the head itself. The valve stem extends outwardly through a suitable screw-plug 17, which acts as a stuffing box and terminates at its outer end in a head 18 which is adapted to receive the usual valve key or wrench. This projecting head of the valve stem, as will be readily seen, occupies a position closely within the angle formed by the head 4 and neck 5, and is, therefore, in a position in which it is not likely to be struck and injured in the handling and use of the container.

charged in through the coupling 21. In the use of the tank or container, the valve 15 is open to the proper extent; and the gas collected by the pipe or tube 12 flows outwardly 5 into the cavity 13, thence through the bushing 16 and outwardly through the passage 19.

22 designates a fusible plug, which is seated in the solid metal of the neck and head, and which controls an escape opening there- 10 through, this plug being of any suitable or well known character, and being designed to fuse or melt, if the temperature to which the container is exposed rises to a danger point.

15 23 designates a safety valve, also seated in the solid metal of neck and head. This safety valve may also be of any usual or well known type, designed to guard against excessive pressure in the container. The open- 20 ings for the plug 22 and valve plug 23 are preferably counterbored so that the plugs will seat entirely within the neck. The manner in which the fusible plug and safety valve are located deep in the metal of the 25 head contributes to the safety of the tank in shipment.

In the modification shown in Fig. 3, I have illustrated the application of my invention to a tank or container in which a pressure gage is not used. In this case, a short cap 6^a is employed in lieu of the long cap 6. The opening 7 is closed by a suitable removable screw plug 24, which will close the outer end of the cavity 13. In this figure I have also shown the inner end portion of the 30 collector pipe or tube as being bent into a position more closely adjacent to the head 4, this being done before the head 3 is closed up. This construction enables an asbestos 35 cloth mat 25 to be placed in the end of the tank through which the gas filters and enters the collecting tube without carrying with it any of the loose asbestos with which the tank is filled and which may have a tendency 40 to clog the tube.

The advantages of my invention will be apparent to those familiar with tanks or 45 containers of this character, since it provides a tank or container which is wholly 50 free from seams; which can be readily manufactured; and in which the parts are effectively protected from injury. The arrangement of the collector pipe or tube, by 55 which it can be extended to the extreme upper portion of the interior of the tank or container, provides for the complete exhaustion of the gas without drawing off any of the solvent. If the collector tube becomes 60 choked or clogged, it can be readily cleaned by forcing a wire or the like therethrough; or it can be readily removed at any time by 65 removing the cap and the gage 9. This tube may, however, be omitted entirely, and the gas allowed to enter directly into the oblique passage 11, since the inner end of

this passage is as far above the level of the solvent as is the case in tanks now generally in use.

It will be noted that the valve 15 is deep-seated within the solid metal of the neck and 70 is thoroughly protected thereby. Its stem is also protected by this solid metal and by the screw plug 17, against lateral blows. The maintenance of the proper conditions of the valve is, therefore, well insured, and the 75 danger of leakage at the valve is reduced to a minimum.

While I prefer to form the head 4 and the neck 5 integral with the body 2, yet many of the advantages of my invention may be ob- 80 tained by forming such head and neck separately and securing them in or to a body 26, as shown in Fig. 5.

What I claim is:—

1. A container for fluids under pressure, 85 comprising a cylinder having an integral thickened end portion forming a combined head and valve casing, said thickened portion having a collecting passage communicating with the interior of the body portion 90 of the cylinder and also having an off-take passage communicating with the collecting passage and extending laterally at an angle to the longitudinal axis of the cylinder, and a valve seated within said thickened portion and controlling the communication between the collecting and offtake 95 passages, said valve having a stem extending laterally within said thickened portion and terminating at its outer end at a point within the circumferential line of said cylinder, substantially as described.

2. A container for fluids under pressure, having a thickened head, said head being provided within the solid metal thereof with 105 two communicating passages extending laterally and out through the side of the head, one of said passages forming a combined gas-charging and outlet conduit, and the other passage having a valve seat, and a 110 valve adapted to said seat and contained wholly within the head and having a laterally protruding stem which lies closely within the angle formed by the head and body; substantially as described.

3. A gas container of the character described, having a solid cylindrical head, said head having a central opening for a gage, and also having a gas-collecting passage whose outer end is closed by the gage, and a 120 valved outlet passage communicating with the said collecting passage, said passage, together with the stem of the valve, extending in a lateral direction, and a gage-protecting cap engaging the exterior of the 125 cylindrical head, substantially as described.

4. A container for fluids under pressure, comprising a cylinder having an integral thickened end portion forming a combined head and valve casing, said thickened por- 130

tion having a collecting passage communicating with the interior of the body portion of the cylinder and also having an offtake passage communicating with the collecting passage and extending laterally at an angle to the longitudinal axis of the cylinder, a valve seated within said thickened portion and controlling the communication between the collecting and offtake passages, and an offtake connection connected to said thickened portion and communicating with

the offtake passage, said connection being made at a point within the circumferential line of said cylinder, substantially as described.

In testimony whereof, I have hereunto set my hand.

WILLIAM WHIGHAM.
